UNITED STATES PATENT OFFICE.

LEE B. MANES, OF ELSINORE, CALIFORNIA.

LUBRICATOR.

No. 803,182.

Specification of Letters Patent.

Patented Oct. 31, 1905.

Application filed October 7, 1904. Serial No. 227,545.

To all whom it may concern:

Be it known that I, LEE B. MANES, a citizen of the United States, residing at Elsinore, in the county of Riverside and State of California, have invented new and useful Improvements in Lubricators, of which the following is a specification.

My invention relates to lubricators; and its primary object is to provide a novel form 10 of lubricator which is adapted to feed lubricant to the bearings of a line-shaft and be automatically operated and controlled by and during the rotation of the line-shaft.

A further object of the invention is to provide means for reconveying an oversupply of lubricant from the drip-nozzle back to the reservoir, thereby preventing waste of lubricant.

Still further objects of the invention will 20 appear as the nature of the same is more fully understood from the accompanying description and accompanying drawings.

The invention consists in the construction, combination, and arrangement of parts hereinafter fully described, claimed, and illustrated in the accompanying drawings, in which—

Figure 1 is an elevation of a lubricator constructed in accordance with my invention 30 and shown in applied position, the pump-cylinder being in longitudinal section. Fig. 2 is a detail side elevation of the striker-arm, showing the manner in which it is applied to the line-shaft.

Referring to the drawings by reference-numerals, 1 indicates a hanger provided with the usual bearing 2, in which is journaled and supported a line-shaft 3. 4 indicates a pump-cylinder fully opened at its upper and lower ends and provided with externally-arranged screw-threads adjacent its ends. The lower end of the cylinder has removably secured thereto a bottom 5, provided with a depending internally-threaded nipple 6, having communication with the interior of the cylinder, the inner surface of said bottom being inclined downward toward its center to adapt it to form a seat for a valve 7, convexed in cross-section. The valve 7 is provided with a centrally-located depending lug 8, adapted to normally fit within the nipple 6 and guide the valve during its movement,

whereby all liability of the valve becoming disengaged and not properly seating itself is obviated.

The cylinder has connection with a reservoir 9 of any preferred construction by means of a feed-pipe 10, the latter having one of its ends connected to the bottom of the reservoir and its other end connected to the 60 threaded portion of the nipple 6. The upper end of the cylinder is normally closed by a removable cap 11, which is provided with a centrally-located aperture 12. Arranged adjacent to the upper end of the cylinder and 65 on the interior thereof is a packing-box 13, formed by relatively arranging in the cylinder reversely-positioned concavo-convex plates 14, which are provided with oppositely-disposed collars 15, centrally arranged 70 and adapted to provide bearings for the reception of a reciprocating piston-rod 16. Secured to the lower end of said piston-rod is a hollow piston-head 17, which is provided with a concaved valve-seat 18, adapted to receive 75 a valve 19, similar in construction to the valve 5. This valve is also provided with a lug 20, which operates to guide said valve in its movement. Positioned between the packing-box and the upper portion of the 80 piston-head 17, is an expansion-spring 21, which acts to normally retain said piston-head in the lower portion of the cylinder or at a point at the extremity of its downward stroke, said downward movement of the piston-head being limited by an annular stop 85 22, secured upon the interior of the cylinder at a point adjacent its lower end. An arm 23 is secured to the cylinder and has its upper extremity projected above the upper end 90 of the cylinder, said extremity being adapted to have pivotally secured thereto an operating-lever 24 to position the free end of said lever in the path of the movement of a striker-arm 25. The lever 24 is secured to the piston-rod 16 by means of a link connection 26. The cylinder is provided with a discharge-opening 27, situated at a point adjacent the packing-box 13, and secured to the cylinder and communicating with said discharge-opening is a feed-pipe 28, having its opposite end connected by means of a union 29 to a drip-nozzle 30. Connected to the upper end 100 of said union is a return-pipe 31, having its

lower end positioned above a funnel 32', secured to the top of the reservoir 9, whereby when an excessive supply of oil is conveyed to the drip-nozzle 30 it will be readily reconveyed back to the reservoir 9 through said pipe 31.

The structure above described is adapted to be secured in its entirety in such position that the discharge end of the drip-nozzle 30 will be positioned above the bearing 2 and the lever will be positioned above and in parallel alinement with the shaft 3, and in order to accomplish this I utilize two bracket-arms, one (indicated by 32) being secured to the hanger 1 and the cylinder 4 and the other (indicated by 33) being secured to any horizontal support and said cylinder. The striker-arm 25 has one of its ends curved in the arc of a circle, as indicated by the numeral 34, and its other end is secured to the shaft 3 by means of a coupling 34^a, said striker-arm being positioned upon the shaft 3 in such a manner that its curved end 34 will engage the free end of the operating-lever 24 during the rotation of the shaft.

The operation of the device may be described in the following manner: It is apparent that during the rotation of the shaft 3 the curved end of the striker-arm 25 will successively engage the free end of the operating-lever 24 and through virtue of its engagement cause said lever to be swung upwardly upon its pivot. This upward movement of the lever 25 will cause the piston-head 17 to correspondingly move upward in the cylinder against the tension of the spring 21, thereby drawing a quantity of lubricant from the reservoir through the pipe 10 into the bottom of the cylinder. As the shaft revolves sufficiently to move the striker-arm out of engagement with the lever 24, the piston-head will be free to be moved downward by the spring 21, thereby unseating the valve 19 and permitting the lubricant which was drawn within the cylinder by the upward movement of the piston-head to flow above said piston-head. When the striker-arm again operates the lever 24, the lubricant above the piston-head will be forced through the pipe 28 to the feed-nozzle 30, from whence it may be fed to the bearing 2 in any desired quantity, the quantity of the feed being regulated by a valve 34^b, positioned in the drip-nozzle. When a greater quantity of lubricant is fed to the drip-nozzle 30 than is necessary, said excess of lubricant will be returned to the reservoir 9 through the pipe 31, and to control and regulate said return I provide a valve 35, which is positioned in said pipe 31.

It is apparent from the above description, in connection with the accompanying draw-

ings, that I provide a lubricator which is automatic in its operation and by means of which a supply of lubricant can be continuously fed to a number of bearings. 65

Having thus fully described the invention, what is claimed as new is—

1. In a lubricator, a bearing, a shaft journaled in said bearing, a reservoir, a pump-cylinder having connection with said reservoir, a piston-rod provided with a piston-head movable in said cylinder, an arm secured to said cylinder, a lever pivotally mounted upon said arm, link connection between said lever and piston-rod, a drip-nozzle having connection with said cylinder, and a striker-arm secured to said shaft and adapted to engage the lever to move the piston-head upward within the cylinder. 70 75 80

2. In a lubricator, a bearing, a shaft journaled in said bearing, a reservoir provided with a funnel, a pump-cylinder having connection with said reservoir, a drip-nozzle having connection with said pump-cylinder, 85 a piston-rod having a piston-head movable in said cylinder, an arm secured to said cylinder, a lever pivotally secured to said arm, link connection between the lever and piston-rod, a striker-arm secured to said shaft and 90 adapted to engage said lever to move the piston-head upward within the cylinder, and a return-pipe adapted to convey an excess of lubricant from the drip-nozzle to said funnel. 95

3. In a lubricator, a bearing, a shaft journaled in said bearing, a reservoir provided with a funnel, a pump-cylinder having connection with said cylinder, a drip-nozzle having connection with said pump-cylinder, a packing-box situated within the upper end 100 of said cylinder and formed by reversely-arranged concavo-convex plates, a piston-rod movable in said packing-box, and having its lower end provided with a piston-head, a spring situated between the packing-box and 105 piston-head to normally retain said piston-head at the limit of its downward stroke, an arm secured to the cylinder, a lever pivotally secured to said arm, link connection between the lever and piston-head, a striker-arm secured to said shaft and adapted to engage said lever to move the piston-head upward against the tension of said spring, and a return-pipe adapted to convey an excess of lubricant from the drip-nozzle to said funnel. 110 115

4. In a lubricator, a bearing, a shaft journaled in said bearing, a reservoir, a pump-cylinder having connection with said reservoir, a packing-box situated within the upper end of said pump-cylinder, a drip-nozzle 120 having connection with said cylinder, a piston mounted within said cylinder, a spring interposed between said packing-box and piston-head to normally retain the piston-

head at the limit of its downward movement, a piston-rod having connection with its piston-head and extending upwardly through the packing-box above said cylinder, an arm

5 secured to said cylinder, a lever pivotally secured to said arm, and a curved striker-arm secured to said shaft and adapted to engage said lever to move the piston-head upward against the tension of said spring, and

means for reconveying an excess of feed to the drip-nozzle back to the reservoir.

In testimony whereof I affix my signature in presence of two witnesses.

LEE B. MANES.
